UNITED STATES PATENT OFFICE

FREDERICK W. SORENSEN, OF BENSON, MINNESOTA.

SCREEN FOR THRESHING-MACHINES.

SPECIFICATION forming part of Letters Patent No. 667,168, dated January 29, 1901.

Application filed March 13, 1900. Serial No. 8,524. (No model.)

To all whom it may concern:

Be it known that I, FREDERICK W. SORENSEN, a citizen of the United States, residing at Benson, in the county of Swift and State of Minnesota, have invented certain new and useful Improvements in Sieves or Screens for Threshing-Machines, &c.; and I do hereby declare the following to be a full, clear, and exact description of the invention, such as will enable others skilled in the art to which it appertains to make and use the same.

My invention relates to sieves or screens especially adapted for use in threshing-machines and fanning-mills, but capable of use independently in any situation where a sieve or screen can be used.

The objects of the invention are to provide an improved sieve or screen in which the meshes may be adjusted to various sizes and shapes to suit the class of work to be done and to otherwise generally improve the construction of such devices. The diagonal position of the square openings with cutting edges in their relation to the longitudinal and transverse adjustments gives a shearing action in each direction of adjustment.

With these objects in view my invention consists in the improved construction, arrangements, and combinations of parts hereinafter fully described and afterward specifically pointed out in the claims.

In the accompanying drawings, Figure 1 is a perspective view illustrating one adaptation of my invention—namely, as an independent mechanism unattached to a machine. Fig. 2 is a longitudinal vertical sectional view of the same. Fig. 3 is a sectional view through a frame above the sieve-plates looking downward in one adjustment of the plates. Fig. 4 is a fragmentary plan view illustrating a portion of the plates in another adjustment. Fig. 5 is a similar view showing a third adjustment. Fig. 6 is a similar view with the sheets in their normal positions. Fig. 7 is a fragmentary sectional view through a portion of the plates in the position shown in Fig. 4. Fig. 8 is a similar view with the sheets in the position shown in Fig. 3. Fig. 9 is a similar view with the sheets in the position shown in Fig. 5. Fig. 10 is a similar view with the sheets in position shown in Fig. 6.

Like numerals mark the same parts in all the figures of the drawings.

As previously stated, my invention pertains exclusively to the construction and means for adjusting the sieve-sheets, and my improved construction is applicable to threshing-machines, fanning-mills, or any other position in which sieves or screens may be used. In this embodiment of my invention I have illustrated it as forming a part of an independent apparatus for performing the function of sifting or screening only, and in this embodiment, as illustrated, 1 indicates a box mounted upon suitable legs or supports 2 and provided with a hopper 3, a discharge-spout 4 at its lower end, a discharge-hopper 5, provided with a sliding door 6, and a hinge-door 7 in its top, the uses of which will be manifest and referred to hereinafter, such construction forming no part of my invention.

8, 9, and 10 indicate, respectively, the upper, middle, and lower sheets of my improved sieve or screen. These sheets are perforated or provided with square holes, the diagonals of which are parallel, respectively, with the sides and ends of the rectangular box or frame in which they are mounted. The upper and lower plates 8 and 10 are stationary, while the middle plate 9 is adjustable between them both longitudinally and transversely, the holes or openings in all of the plates being of the same size and shape and in their normal positions, as illustrated in Figs. 6 and 10, 85 registering with each other, leaving the holes of their full size. In order to move the plate 9 longitudinally, it is extended, as at 11, beyond the ends of the frame and provided with a rack 12, which is engaged by a pinion 13 on a shaft 14, journaled in bearings 15, secured to the frame, such shaft being provided with cranks 16 at its ends, whereby it may be rotated. When the shaft is rotated, the plate 9 will be moved longitudinally, the first movement from the position shown in Figs. 6 and 10 being to that shown in Figs. 4 and 7, the movement being substantially one-half the diagonal length of the holes. In this adjustment the sizes of the holes are reduced to substantially one-fourth of their original size, thus adapting the complete screen to the uses

of a screen with such smaller perforations or holes. It will of course be understood that this longitudinal movement may be limited, so as to decrease the size of the holes to any desired degree between the sizes illustrated in Fig. 6 and those in Fig. 7. What may be termed the "second" adjustment is effected by moving the middle sheet in the same direction beyond the position to which it was moved to bring the parts to the position shown in Fig. 4. This adjustment is illustrated in Fig. 3 and results in dividing each large hole of the sheet into four small holes, making in effect a screen with an extremely fine mesh. What might be termed the "third" or "double" adjustment is effected by first moving the middle sheet longitudinally to about the position for effecting the first adjustment, as illustrated in Fig. 4, and then transversely to the position shown in Fig. 5, in which each large hole is divided into two holes of the same length, but substantially of one-third the width. This last adjustment is effected by any suitable means—for instance, by a crank-and-pinion mechanism similar to that used for effecting the longitudinal adjustment, as illustrated in Fig. 3, in which mechanism 18 indicates a rack on the plate 11, and 19 a pinion engaging it, said pinion being secured on a shaft 20, journaled in stationary bearings 21. The pinions 13 and 19 are both elongated, as shown, to permit them to slide transversely in the racks, each pinion sliding in its rack when the plate is moved by the other pinion. The shaft 20 is provided with a crank 22, by means of which it may be turned to reciprocate the plate 11 laterally. In sheets 8 and 10 the holes or edges of the openings are beveled downward, as shown at 40 17, so as to present a knife-edge in moving the sheet in either direction. By this means any long refuse, such as straw or light twigs, may be cut off by reciprocating the middle sheet.

45 It will of course be understood that the frame in which my improved sieve is mounted may be stationary or movable or horizontal or inclined and any ordinary means pro-

vided, where the frame is movable, for effecting such movement, such means forming no part of my invention.

In the operation of my invention the sieve will be used in the same manner in which sieves of well-known constructions are used, the material to be screened being passed into the hopper 3 and discharged through the spout 4, the material which passes through the meshes of the sieve being discharged by opening the door 6.

The simplicity of construction of the plates, which may be made of any material suitable for such purposes, will enable the sieve to be economically constructed, and by means of the adjustments hereinbefore described the range of usefulness of a single sieve will be very greatly extended.

Having thus described the invention, what is claimed, and desired to be secured by Letters Patent, is—

1. A sieve comprising three superposed sheets in contact with each other, each sheet provided with square holes set diagonally with reference to the edges of the sheets, the upper and lower sheets being stationary, and means for adjusting the middle sheet longitudinally and transversely, substantially as and for the purpose described.

2. A sieve comprising three superposed sheets in contact with each other, the upper and lower sheets of which are stationary, each sheet being provided with normally-registering holes, those portions of the top and bottom sheets which form the edges of the holes being beveled inward to knife-edges, and the walls of the holes of the middle sheet being at right angles to the sheet, in combination with means for adjusting the middle sheet longitudinally and transversely, substantially as and for the purpose described.

In testimony whereof I affix my signature in presence of two witnesses.

FREDERICK W. SORENSEN.
